(57) **CLAIM**

We claim the ornamental design for a printer, as shown and described.

DESCRIPTION

FIG. 1 is a top perspective view of a printer showing our new design;

FIG. 2 is a front elevational view thereof;

FIG. 3 is a left-side elevational view thereof, the right-side elevational view being a mirror image of FIG. 3;

FIG. 4 is a top plan view thereof;

FIG. 5 is a rear elevational view thereof; and,

FIG. 6 is a top perspective view of the printer of FIG. 1 illustrating a scanning lid of the printer in a raised position. The broken lines in the drawings are for illustrative purposes only and form no part of the claimed design.
